UNITED STATES PATENT OFFICE.

JOSEPH CORRIGAN, OF ROCKLEDGE, PENNSYLVANIA.

LOOM FOR WEAVING TERRY FABRICS.

Application filed April 9, 1919. Serial No. 283,701.

To all whom it may concern:

Be it known that I, JOSEPH CORRIGAN, a citizen of the United States, and a resident of Rockledge, county of Montgomery, State 5 of Pennsylvania, have invented certain new and useful Improvements in Looms for Weaving Terry Fabrics, of which the following is a specification.

My invention relates to looms which are 10 adapted to be employed for weaving terry fabrics and it has for its object, generally speaking, to simplify and render more efficient the mechanical construction of such looms and thereby also reduce the cost of 15 manufacture.

A further object of my invention is to provide a construction in which the race-plate and the lay are so constructed and related to each other as to avoid the collection 20 of dust, ravelings, etc., in a way to interfere with the proper operation of the race-plate and the reed having connection therewith.

In the construction as shown the race- 25 plate comprises a metal plate (such as steel) situated adjacent the lay and to the top side of which a thinner plate of less width is secured. The shuttle travels back and forth over the race plate. The steel plate 30 is of a width substantially equal to that of the lay and substantially covers the same.

Movement of the said race-plate and reed connected therewith relatively to the lay is effected for the usual known purpose.

For accomplishing the above mentioned 35 purpose or object the construction is such that the race-plate is not permitted to abut against a shoulder or other abutment. In consequence there can be no collection of 40 dust, ravelings, etc., to interfere with the proper movements and operation of the race-plate during the weaving of a terry fabric in which operation there is, as is well known, relative movements between the 45 race-plate and the reed and the lay.

Another object of my invention is to provide the means for causing relative movement between the race-plate and a portion of the reed connected therewith and the lay 50 with adjustments whereby the extent of such relative movement may be varied; also to simplify the construction of said means.

My invention also has for its object to provide a simple and efficient means whereby 55 the operation of the mechanism for weaving terry cloth or fabric may be auto-

matically discontinued without interfering with the operation of the loom so that in the further operation smooth or plain cloth will be woven. The period during which 60 such mechanism is thrown out of operation is controlled so that automatically at the expiration of a certain predetermined time and after a predetermined length of such plain or smooth cloth has been woven the 65 terry weaving mechanism is again thrown into operation and the weaving of terry fabric is resumed. It is apparent, therefore, that this mechanism provides means whereby the length of the sections of terry fabric 70 and the intermediate lengths of smooth or plain cloth to be woven may be controlled and varied as desired.

Other objects and advantages of my invention will be referred to in the detailed 75 description thereof which follows or will be apparent from such description.

In order that my invention may be more readily understood and its practical advantages fully appreciated reference should be 80 had to the accompanying drawings in which I have illustrated one form of a convenient embodiment thereof. It will be understood, however, that the said invention is susceptible of embodiment in other forms of construction than that shown.

In the drawings:

Figure 1 is a vertical sectional view taken from front to rear along the line 1—1 of Fig. 3, parts of the construction being shown 90 in side elevation and parts of the loom construction being omitted in order that the parts constituting the invention may be more clearly shown;

Fig. 2 is an enlarged transverse sectional 95 view taken on the line 2—2 of Fig. 3 with a portion of one of the parts broken away to show another part more clearly;

Fig. 3 is a horizontal sectional view taken through the upper part of the loom structure, the portions of the structure constituting the invention being shown in top plan view; and

Fig. 4 is a view in front elevation of a portion of a loom structure showing in front 105 elevation a portion of the structure constituting one feature of my invention.

Referring to the drawings, 1 designates the frame of the loom and 2 the lay supported upon lay swords 3, there being one 110 at each end of the loom and each being connected at its upper end to the outer end of

the lay 2. At their lower ends the lay swords 3 are pivoted in known manner to the opposite sides of the loom frame.

Rocking or oscillatory motion is imparted 5 to the lay by means of crank arms 4 upon a crank shaft 5, which is provided at one end with a gear 6 in engagement with a larger gear 7 mounted upon a main shaft 8, from which the mechanism of the "terry" attachments 10 is actuated. At its opposite end from the gear 6 the shaft 5 is provided with a wheel 9 driven by a belt (not shown) to rotate the shaft 5.

The crank arms 4 are connected with the 15 lay swords 3 by means of connecting rods or links 10. It is apparent that rotation of the shaft 5 causes a rocking or oscillatory movement of the lay 2 which is secured to the upper ends of the lay swords.

20 In addition to the gear 7 the main shaft 8 is also provided with a small gear 15 which is in engagement with a larger gear 16 mounted upon a shaft 17, which shaft is mounted in bearings 18 supported in cross-girts 19 extending from front to rear of the loom frame and being supported at their opposite ends upon the front and rear cross-pieces of the loom frame structure.

25 In the construction shown the gear 15 is provided with thirty teeth while the gear 16 is provided with forty-five teeth.

The shaft 17 is also provided with a cam 20 having oppositely disposed high or dwell portions 21 and 22 and intermediate depressions 23 and 24, the said portions and the 30 said depressions being situated in opposing relation to each other as shown. The high or dwell portion 21 is considerably longer or wider than the opposing high or dwell portion 22. The said cam 20 is adapted to contact and co-operate with a contact wheel 25 supported upon a lever 26 pivoted at 27 intermediate its ends and extending longitudinally of the loom structure. Depending 35 from the said lever is an arm 28 to the lower end of which the front end of a strong coiled spring 29 is secured. The rear end of the said spring is connected to an arm or projection 30. This arm may have 40 connection with any fixed or stationary portion of the loom structure. In the construction shown it is connected with the adjacent cross-girt 19.

The tension of the spring 29 acting upon 45 the depending arm 28 tends to force the portion of the lever 26 in rear of its pivot 27 in an upward direction so as to hold the wheel 25 in contact with the periphery of the cam member 20. At its rear end the 50 lever 26 is slotted, which slot provides means for adjustably connecting the lower end of a link 35 thereto. The upper end of the 55 said link is adjustably connected in a slot 36 in the end portion of the forwardly projecting arm 37 of a bell crank lever 38 se-

cured to a rock-shaft 39. The other arm 40 of the said bell crank extends downwardly and is provided with a number of holes 41 adjacent to its lower end to provide for adjustably connecting the rear end of a connecting rod 42 thereto. The front end of said connecting rod is connected to the lower end of an arm 45 depending from a rock-shaft 46 journaled at its opposite ends in bearings 47 formed in projections or lugs 75 which depend from U-shaped members 50 which are secured to the lay 2.

The opposite side portions of the said members 50 project above the top surface of the bole of the lay 2 and are provided with 80 bearings 52 in which the opposite hardened ends 53 of the bars 54 are slidably or movably mounted. These bars extend across and in close proximity to the upper surface of the lay.

85 The race-plate is secured to and supported upon these bars, said plate comprising the plate or bar 56 of suitable metal, such as steel, which is secured to the said bars 54 and a narrower plate 57 secured on the top 90 of the plate or bar 56 by means of screws 58. 60 designates a groove extending longitudinally of the plate or bar 56, said groove being provided as a seat or bearing for the lower bar of the reed 61. The rear edge of 95 the plate 57 is curved and fitted against the cylindrical surface of the lower bar of the reed as shown, the construction being such as to permit the turning or rocking of the lower bar of the reed in its seat, said bar 100 being prevented, however, from becoming accidentally disengaged therefrom.

The rock shaft 46 is provided with arms 105 adjacent its opposite ends which extend upwardly therefrom and are pivotally connected at their upper ends to the rear ends 71 of strips or bars 72 of suitable material which extend underneath and are secured by means of screws 73 to the lower side of the plate or bar 56 of the race-plate.

110 If the lever 26 is left free to oscillate or rock upon its pivot it will be apparent that as the cam 20 rotates the said lever is rocked or moved about its pivot and that such rocking movement through the connections 35, 38, 40, 45 and 70 causes oscillating or reciprocatory movement of the race-plate (comprising the plates 56 and 57) independent of the movements imparted to the lay, the race-plate and the reed by means of the 115 crank arms 4 and connecting rods or links 10, as previously described.

When the contact wheel 25 drops into the recesses or depressions 23 and 24 of the cam 20 the movement of the connections 35, 38, etc., causes rearward movement of the race-plate and reed with the result that two of the picks or weft threads are left loose and are not jammed or pushed up tight against the edge of the cloth being woven.

During the period that the long high part or dwell 21 of the cam 20 is traveling in contact with the contact wheel 25, at which time the race-plate is held in forward position, a third pick or weft thread is thrown or shot and all three picks or weft threads, including the two which have been left loose by reason of the presence of the depressions 23 and 24, are forced or pushed 10 up tight against the edge of the cloth being woven and the loops in certain of the warp threads are formed thereby producing a fabric known or called "terry." These loops are formed in certain of the warp threads which are not drawn tight or taut.

The height of these loops may be varied by varying the distance through which the race-plate moves relatively to the lay. This adjustment may be effected by changing the 20 points of connection of the opposite ends of the link 35 to the lever 26 and to the arm 37 of the bell crank lever 38 and also the point of connection of the rear end of the connecting rod 41 to the lower end portion 25 of the arm 40 of the said bell crank lever.

If a higher loop is desired the adjustment should be made to cause a longer or greater movement of the race plate and reed relative to the lay 2.

30 In the weaving of fabrics containing terry portions it is frequently desirable that means be provided not only for interrupting or discontinuing the operation of the "terry" mechanism and during such discontinuance permitting or causing the weaving of a plain or smooth fabric but such means should also determine or be capable of determining the length of the terry portions and the intermediate smooth or non-terry 35 portions of the fabric.

As a means or mechanism for accomplishing this desirable result I have provided a relatively short shaft 80 mounted in bearings 81 and 82 supported upon the 45 front portion of the frame structure of the loom at one side thereof adjacent to the take-up gear mechanism common to loom structures. 83 designates a gear mounted on the shaft 80, which gear is in engagement with a gear 84, the latter being one of a train of gears for operating the take-up roll. The other gears of said train are not shown. The said shaft 80 is also provided with a sprocket wheel 85 with which a 50 sprocket chain 86 is engaged and over which the said chain is caused to travel. The links of said chain are separable so that its length may be increased or diminished as desired.

The chain is provided with one or more 60 links having projections such as 87 thereon. In the construction shown two adjacent links of the chain are provided with projections. It will be understood that links in addition to and situated a distance from 65 those shown with projections may also be

provided with projections and that by reason of the presence of projections at intervals in the chain the periods during which the "terry" mechanism is allowed to remain operative is varied and consequently the 70 length of terry fabric which is woven may be controlled or else a greater or less number of links may be removed or inserted in the chain to lengthen or shorten the same to thereby control the length of a terry section of the fabric which is being woven.

The projections 87, whether one or more groups thereof, contact with the outer end portion of an arm 90 of a bell crank lever 91. The other arm 92 of the said bell crank 80 lever extends as shown in Fig. 1 of the drawings toward the bottom of the loom structure and is connected at its lower end to a link 93, the opposite end of said link being connected to an arm 94 upon a rock 85 shaft 95 supported in bearings 96 secured to the front lower cross-bar 96^a of the frame of the loom. The shaft 95 is provided at its opposite end portion with an arm 97 having a pin 98 in engagement with a slot 99 90 in the upper end portion of a dog 100 pivotally supported at 101. The said dog is provided with a forwardly extending projection 102 slotted or notched as indicated at 103. A portion of the cross-bar 96^a projects into the said slot or notch 103 to limit the extent of pivotal movement of the dog 100. When the dog 100 is moved rearwardly it is adapted to engage a shoulder 104 upon the forward end of the lever 26. When in 100 engagement with the said shoulder such dog prevents operation of the said lever.

The arm 90 of the bell crank lever 91 is provided with a weight 105, which, when the smooth part of the sprocket chain 86 is 105 in operative relation to the said arm 90, holds the said bell crank lever in the position shown in Fig. 1 of the drawings, in which position the dog 100 is held out of engagement with the shoulder 104 upon the 110 front end of the lever 26 leaving the said lever free to oscillate or rock. When projections, such as 87, upon the sprocket chain 86 contact with the arm 90 of the bell crank lever 91 movement thereof is effected to 115 throw the dog 100 into engagement with the said shoulder 104 and thereby prevent operation or pivotal movement of the lever 26 so that the same is not permitted to move when the depressions 23 and 24 of the cam 120 20 are brought into operative relation to the contact wheel 25. The result, therefore, is that when the dog 100 is in engagement with the said lever to prevent operation thereof relative movement of the race-plate with 125 respect to the lay is prevented and in consequence each pick weft thread is forced up tight against the edge of the cloth being woven to produce a plain or smooth cloth as distinguished from terry cloth or fabric.

130

As soon as a sprocket chain has so moved as to carry a projection or projections 87, as the case may be, out of contact with the arm 90 the weight 105 causes movement thereof and of the parts connected therewith to disengage the dog 100 from the lever 26 to permit operation of the latter by the cam 20 and a consequent resumption of the weaving of the terry fabric.

10 The length of time during which the arm 90 is held in elevated position by projections 87 determines the length of the portions of smooth or plain fabric intermediate the terry sections. Likewise the length of 15 time during which the said arm 90 occupies its lower position, as when resting upon the links of the sprocket chain other than those provided with the said projections, determines the length of the terry sections.

20 I claim:

1. In a loom of the character described, the combination of a lay, pivoted arms for supporting the same, means for causing oscillatory movement of the said lay, bearings supported upon opposite sides of the opposite end portions of said lay, bars slidably supported in the said bearings, a race-plate secured to the said bars and means for causing reciprocatory movement of the said race-plate independently of the oscillatory movement of the said lay.

2. In a loom of the character described, the combination of a lay, means for supporting the same, means for causing oscillatory movement of the said lay, a race-plate, means for supporting said race-plate out of contact with said lay, a cam, a lever having contact with the said cam and adapted to be actuated thereby and connections 35 intermediate the said lever and the said race-plate whereby actuation of the said lever causes actuation of the said race-plate independently of the oscillatory movement of the said lay.

40 3. In a loom of the character described, the combination of a lay, means for causing oscillatory movement thereof, a race-plate, a rock shaft, connections between the said rock shaft and the said race-plate, an arm depending from the said rock shaft, means for rocking the said last mentioned arm to cause movement of the said race-plate independently of the said lay.

45 4. In a loom of the character described, the combination of a lay, means for causing oscillatory movement thereof, bearings supported upon said lay, bars slidably mounted in said bearings, a race-plate supported upon said bars above and in approximate 50 and parallel relation to the lay, a rock shaft, means carried by the said lay for supporting said rock shaft, arms having rigid connection with the said rock shaft and pivoted connection with the said race-plate, an additional arm having rigid connection with the

said rock shaft and means for causing rocking movement of the last mentioned arm and thereby causing rocking movement of the said first named arms to effect back and forth movement of the said race-plate.

5. In a loom of the character described, the combination of a lay, means for causing oscillatory movement thereof, a race-plate situated above and in approximate and parallel relation to the said lay, a cam, means for causing rotation of said cam, a plurality of levers intermediate the said cam and the said race-plate, one of the said levers being adapted to be actuated by the said cam to cause actuation of the other of said levers to 75 cause actuation of the said race-plate and adjustable connections between said levers, substantially as described.

6. In a loom of the character described, the combination of a lay, means for causing oscillatory movement thereof, a race-plate, a cam, means for causing rotary movement of said cam, a lever situated in adjacent relation to said cam, means for holding said lever in contact with said cam, a bell crank lever, a connection between the cam actuated lever and an arm of the said bell crank lever, means for adjusting said connection so that movement of the cam actuated lever will vary the throw of the said bell crank lever, a rock shaft, connections between the said rock shaft and the said race-plate and connections between the said rock shaft and the other arm of said bell crank lever whereby movement of the said bell crank lever 80 will cause rocking movement of the said rock shaft to cause back and forth movement of the said race-plate.

7. In a loom of the character described, the combination of a lay, means for causing oscillatory movement thereof, a race-plate, a cam, means for causing rotary movement of said cam, a lever situated in adjacent relation to said cam, means for holding said lever in contact with said cam, a bell crank lever, a connection between the cam actuated lever and an arm of the said bell crank lever, means for adjusting said connection so that movement of the cam actuated lever will vary the throw of the said bell crank 95 lever, a rock shaft, an arm having rigid connection with the said rock shaft and a connection between the said arm and the other arm of said bell crank lever whereby rocking movement of the latter caused by movement of the said cam actuated lever causes rocking movement of the said rock shaft to cause back and forth movement of the said race-plate.

8. In a loom of the character described, the combination of a lay, a race-plate supported in operative relation to the said lay, a cam, a pivoted lever situated in adjacent relation to said cam, means for yieldingly holding a portion of said lever in contact 100

- with the said cam, a pivoted arm situated a distance from the said cam actuated lever, a link connecting the said lever and the said arm, means for varying the connections between the said link and the said lever and arm, a second arm having rigid connection with the first named arm and extending at an angle with respect thereto, the said arms being actuated by the actuation of the said cam actuated lever and connections between the end portion of the second named arm and the said race-plate whereby actuation of the said arm causes actuation of the said race-plate.
15. 9. In a loom of the character described, the combination of a lay, means for causing oscillatory movement thereof, a race-plate, a cam, connections intermediate the said cam and the said race-plate whereby the said cam is adapted to cause movement of the said race-plate independently of the movement of said lay and a device for engaging the said connections to prevent operation thereof and thereby prevent movement 25 of the said race-plate independently of the said lay.
10. In a loom of the character described, the combination of a lay, means for causing oscillatory movement thereof, a race-plate, 30 a cam, connections intermediate the said cam and the said race-plate whereby the said cam is adapted to cause movement of the said race-plate independently of the movement of said lay, a device for engaging 35 said connections to prevent operation thereof and thereby prevent movement of the said race-plate independently of said lay and automatically acting means for causing movement of said device into engagement 40 with the said connections.
11. In a loom of the character described, the combination of a lay, means for causing oscillatory movement of said lay, a race-plate, means for causing oscillatory movement of said race-plate independently of the movement of said lay, take-up gear mechanism, a device which is adapted to engage a part of the means for causing independent movement of the said race-plate 45 to prevent operation of the said means and mechanism intermediate the said take-up gear mechanism and the said device for causing movement of the latter into engagement with the said part.
55. 12. In a loom of the character described, the combination of a lay, means for causing oscillatory movement thereof, a race-plate, means for causing movement of said race-plate independently of the movement of said 50 lay, said means comprising a lever, a pivoted dog adapted to be engaged with and disengaged from said lever and means for automatically moving said dog into engagement with said lever.
60. 13. In a loom of the character described, the combination of a lay, means for causing oscillatory movement thereof, a race-plate, a rotary cam, connections intermediate the said cam and the said race-plate, said connections being adapted to be actuated by 65 said cam to cause movement of said race-plate independently of the said lay, a pivoted device and means for causing pivotal movement of said device at intervals into engagement with a part of said connections 70 to prevent actuation thereof by the said cam.
14. In a loom of the character described, the combination of a lay, means for causing oscillatory movement thereof, a race-plate, 75 a rotary cam, a lever adapted to be actuated by said cam, connections between said lever and the said race-plate whereby actuation of the lever causes movement of the said connections to actuate the said race-plate independently of the said lay, a device adapted 80 to be moved into engagement with the said lever to prevent actuation thereof and means for automatically moving said device into engagement with said lever.
15. In a loom of the character described, 85 the combination of a lay, means for causing oscillatory movement of said lay, a race-plate, means for slidably supporting the said race-plate, a rotary cam, a lever pivoted intermediate its ends, means for yieldingly 90 pressing one portion of said lever upon one side of its pivot in contact with the said cam, connections between the said last mentioned portion of said lever and the said race-plate whereby pivotal or swinging 95 movement of said lever causes back and forth movement of the said race-plate and a device adapted to engage the portion of said lever upon the opposite side of its pivot 100 to prevent pivotal movement thereof in one direction and thereby prevent movement of 105 said race-plate.
16. In a loom of the character described, the combination of a lay, means for causing oscillatory movement of said lay, a race-plate, means for slidably supporting the said race-plate, a rotary cam, a lever pivoted intermediate its ends, means for yieldingly 110 pressing one portion of said lever upon one side of its pivot in contact with the said cam, connections between the said last mentioned portion of said lever and the said race-plate whereby pivotal or swinging movement of said lever causes back and forth movement of the 115 said race-plate, a pivoted device adapted to be moved at intervals into engagement with the portion of said lever upon the opposite side of its pivot to prevent pivotal movement thereof in one direction and thereby 120 prevent back and forth movement of the said race-plate and automatically acting means for causing movement of the said pivoted device at intervals into and out of engagement 125 with the said lever.

17. In a loom of the character described, the combination of a lay, means for causing swinging movement thereof, a race-plate, means for causing movement of said race-plate relatively to the said lay independently thereof, a rotatable shaft, a chain on said shaft, a bell crank lever having one arm in operative relation to said chain, the said chain having one or more projections thereon for contacting with the said arm to lift the same, a pivoted device adapted to be moved into and out of engagement with a part of the means for causing movement of the said race-plate and connections intermediate the said device and the other arm of 15 said bell crank lever whereby swinging movement of said lever causes swinging movement of the said device into and out of engagement with said part.
18. In testimony that I claim the foregoing 20 as my invention, I have hereunto signed my name this 3rd day of April, A. D. 1919.

JOSEPH CORRIGAN.
